UNITED STATES PATENT OFFICE.

PHILEMON O. DICKINSON, OF NEWARK, NEW JERSEY.

DESIGN FOR A POCKET-BOOK, &c.

SPECIFICATION forming part of Design No. 25,601, dated June 9, 1896.

Application filed April 30, 1896. Serial No. 589,785. Term of patent 3 $\frac{1}{2}$ years.

To all whom it may concern:

Be it known that I, PHILEMON O. DICKINSON, a citizen of the United States, residing at Newark, in the county of Essex and State of New Jersey, have invented and produced a new and original Design for Pocket-Books and Similar Articles, of which the following is a specification, reference being had to the accompanying drawings, which illustrate the design.

The present design relates to a border in metal to be applied to an edge and to adjacent corners of the flap or similar part of a pocket-book or similar article.

In the drawings, Figure 1 represents a face or plan view of the design. Fig. 2 represents a detail cross-section on *a a* of Fig. 1 of the metal bearing the design and which incloses the edge of the flap or other part of the pocket-book or similar article.

Referring to the design in detail, the same consists in essential style of a rococo pattern arranged in elements as follows: A is a piece or part of the design running along one edge of the flap of the pocket-book, which flap is represented by the dotted lines, together with the outline of the design, as shown in Fig. 1. This design, part A, extends to one of the rounded corners B of the flap. Along the

lower edge of the flap runs a design-border C, of similar general characteristics, to the opposite corner D. Along the opposite vertical edge of the flap the design, in same general characteristics, extends up the edge of the flap, as shown at E, but not to such a distance as does the border A on the opposite edge. Intermediate designs, such as F and G, are introduced in manner to produce a rosette-like design H and I at each corner of the flap, while in similar manner a shield-like design J is formed in the middle of the flap by the parts K and L.

In Fig. 2, M represents the metal composing the upper or face part of the flap, which bears the design, while N represents the clasp or border part, which passes over the edge of the leather or other material of the flap and under the same to secure the metal bearing the design to the flap.

What is claimed as new is—

The herein design for pocket-books and similar articles, substantially as shown and described.

PHILEMON O. DICKINSON.
